UNITED STATES PATENT OFFICE.

THOMAS LALOR, OF TORONTO, ONTARIO, CANADA, ASSIGNOR OF ONE-HALF
TO WILLIAM HAMILTON, OF SAME PLACE.

LATCH.

SPECIFICATION forming part of Letters Patent No. 257,725, dated May 9, 1882.

Application filed August 29, 1881. (Model.)

To all whom it may concern:

Be it known that I, THOMAS LALOR, of the city of Toronto, in the county of York, in the Province of Ontario, Canada, have invented 5 certain new and useful Improvements in Locks, of which the following is a specification.

The object of the invention is to produce a simply-constructed and strong lock specially designed for prisons, and which cannot easily be strained or otherwise put out of order; and it consists essentially of a cylindrical block pivoted within a lock-frame and having a vertical slot cut in it to receive the bar of the gate it is intended to secure, the said lock being so 10 connected to the latching and locking mechanism that no strain can be exerted through it to the said mechanism, as hereinafter more particularly explained.

In the drawings, Figure 1 is a portion of a 20 prison-wall with my improved rotary lock set in position and exhibiting the gate or door locked. Fig. 2 is a perspective view of the lock with a portion of the frame removed and exhibiting the position of the cylindrical block and tumblers when the block is set to receive the bar. Fig. 3 is a similar view of the lock, showing the cylindrical block in the position it will appear when the gate is closed and latched. Fig. 4 is a similar view, showing the 25 position of the tumblers when the block is locked.

In the drawings, A represents a portion of a stone wall forming a jamb of the door leading into a cell.

B is the door or gate of the cell.

C is a cylindrical block, provided with a spindle, D, and pivoted within the frame E. The spiral spring F is arranged to hold the block in the position shown in Fig. 2 when not otherwise acted upon.

G is a notch cut in the block C, sufficiently large to receive the end bar of the door or gate B, or a bar attached thereto.

H is a wing or projection attached to or 45 forming part of the cylindrical block.

I is a tumbler operated by the key, and having a foot arranged to fit between the wing H and frame of the lock when the cylindrical block has been changed from the position

shown in Fig. 2 to the position it is exhibited 50 in Fig. 3, where the lock is shown latched.

J is a tumbler, also operated by the key, and designed to fit over the foot of the tumbler I, in order to hold it down, and thereby lock the lock, as shown in Fig. 4. The other tumblers 55 exhibited in the lock are of the ordinary kind, designed to prevent the lock being picked.

K is a semicircular guard-piece, extending from the back of the lock around a portion of the circumference of the cylindrical block C, 60 as shown. When the door or gate B is opened the notch G in the cylindrical block C should be in the position it is shown in Fig. 2. When the gate is closed the end bar comes in contact with the inner side of the notch, pushing 65 the block around upon the spindle till the notch reaches the position shown in Fig. 3, by which time the wing or projection H will have been carried from the position shown in Fig. 2 to the position in which it is shown in Fig. 70 3, when the latch-tumbler I drops down behind it, thereby holding the block stationary, and securing the end bar of the gate between the notch and guard-piece K, as shown in Fig. 1. In order to fasten it in this position doubly 75 secure, the key is turned so that the locking-tumbler J is thrown forward till it rests upon the foot of the tumbler I, as shown in Fig. 4, preventing the latter tumbler being raised from behind the wing H. In order to open 80 the door, the key is turned in the usual direction, when it first withdraws the tumbler J from the position it is shown in Fig. 4 to the position shown in Fig. 3. The next movement 85 of the key raises the tumbler J clear of the wing H, which action releases the cylindrical block C, permitting it to be turned upon its spindle by the tension of the spring F, which causes the notch to change from the position in which it is shown in Fig. 3 to the position 90 shown in Fig. 2, thereby permitting the gate to be opened.

It will be noticed from the description that there is no connection between the cylindrical block C and the tumblers of the lock, except 95 when the latch is locked, and even then there can be no injurious strain exerted on the tumblers by any pressure which may be directed

against the block C. If the notch be accidentally turned into the position shown in Fig. 3 while the gate is open, the strain directed against the lock by the end bar of the gate coming in contact with the latter will be sustained entirely by the block and its spindle, and will not be communicated to the tumblers, which are necessarily delicate as compared with the block. Consequently the durability of the lock is insured.

What I claim as my invention is—

A cylindrical block having a notch, G, to

receive the bar of the gate, and pivoted in the frame of a lock provided with a semicircular guard-piece, K, in combination with a wing or projection, H, attached to or forming part of the cylindrical block C, and arranged in connection with the tumbler I, substantially as and for the purpose specified.

THOMAS LALOR.
